CLAIM

The ornamental design for a head injury trigger system as shown and described.

DESCRIPTION

FIG. 1 is a front perspective view of a head injury trigger system according to an embodiment of my new design for a head injury trigger system.

FIG. 2 is a rear perspective view of the head injury trigger system of FIG. 1.

FIG. 3 is a front view of the head injury trigger system of FIG. 1.

FIG. 4 is a back view of the head injury trigger system of FIG. 1.

FIG. 5 is a left side view of the head injury trigger system of FIG. 1.

FIG. 6 is a right side view of the head injury trigger system of FIG. 1.

FIG. 7 is a top view of the head injury trigger system of FIG. 1; and,

FIG. 8 is a bottom view of the head injury trigger system of FIG. 1.

The broken lines show portions of the head injury trigger system that form no part of the claimed design.
